PAUL N. BOSSART, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed April 4, 1930. Serial No. 441,517.

My invention relates to railway traffic controlling apparatus, and particularly to apparatus of the type comprising train-carried governing means cooperating with devices 5 located at intervals along the trackway.

I will describe one form of apparatus embodying my invention, and will then point out the novel features thereof in claims.

In the accompanying drawing, Fig. 1 is a 10 diagrammatic view illustrating one form of railway traffic controlling apparatus embodying my invention. Fig. 2 is a diagrammatic view showing an alternate arrangement of a portion of the apparatus illustrated 15 in Fig. 1.

Similar reference characters refer to similar parts in both views.

Referring to the drawing, the reference characters 1 and 1^a designate the track rails 20 of a stretch of railway track over which traffic normally moves in the direction indicated by the arrow. These track rails are divided, by means of insulated joints 2, into a plurality of successive track sections A—B, 25 B—C, C—D, etc. Each track section is provided with a track circuit comprising a suitable source of current, here shown as a battery 3, connected across the rails adjacent the exit end of the section, and a track relay, 30 designated by the reference character T with an exponent corresponding to the location, and connected across the rails adjacent the entrance end of the section.

Each track section is also provided with a 35 polarized line relay designated by the reference character E with an exponent corresponding to the location. Each line relay E is controlled by the track relay T for the associated section, and by the track relay T and line relay E for the section next in advance of the associated section. Referring 40 particularly to line relay E^B, for example, when track relays T^B and T^C are both energized, and when line relay E^C is deenergized, line relay E^B is energized in the reverse direction so that polar contact 9 is swung to the right, current flowing from a suitable source, such as a battery Q^C, through line wire 17, winding of line relay E^B, wire 18, front contact 6 of track relay T^B, line wire 19, front

55 contact 5 of track relay T^C, wire 20, back contact 7 of line relay E^C, and wire 21 back to battery Q^C. When track relays T^B and T^C and line relay E^C are all energized, however, line relay E^B is then energized in the normal direction to swing contact 9 to the left, current then flowing from a battery P^C through wire 29, front contact 7 of line relay E^C, wire 20, front contact 5 of track relay T^C, line wire 19, front contact 6 of track relay T^B, wire 18, 60 winding of line relay E^B, and line wire 17 back to battery P^C.

65 Located adjacent the entrance end of each section is a trackway signaling device designated by the reference character N with an exponent corresponding to the location. Each signaling device N, as here shown, comprises three transmitters L¹, L² and L³, each adapted, when energized, to transmit a beam 70 of radiant energy toward a corresponding train-carried relay device as the train passes the associated signaling device N, for controlling train-carried governing means as will be explained more fully hereinafter. Each of these transmitters may have any suitable 75 form. For example, in the form illustrated in the drawing, each transmitter L comprises an electric lamp which may be provided with a suitable optical system, and which is arranged to transmit a beam of light rays towards the train as the train passes the associated signaling device.

80 Each signaling device N is controlled by the associated track relay T and line relay E. Referring particularly to signaling device N^B, for example, when track relay T^B is energized and line relay E^B is deenergized, the electric lamp of transmitter L² of this signaling device is energized by current which flows from a suitable source of current, such as a battery U^B, through wires 10, 11 and 12, the electric lamp of transmitter L², wires 13 and 14, back contact 8 of line relay E^B, wires 32 and 15, front contact 4 of track relay T^B, and wire 16 back to battery U^B. The 85 electric lamp of transmitter L² of signaling device N^B is also energized when track relay T^B is energized and line relay E^B is energized in the normal direction by virtue of a branch for the circuit just traced, this branch passes 90

ing from wire 13 through wire 30, normal contact 9 of line relay E^B , and wire 31 to wire 15. When track relay T^B is energized and line relay E^B is energized in either direction, the electric lamp of transmitter L^1 of signaling device N^B is then energized, the circuit for this lamp being from battery U^B , through wire 10, electric lamp of transmitter L^1 , wire 22, front contact 8 of line relay E^B , wires 32 and 15, front contact 4 of track relay T^B , and wire 16 back to battery U^B . The electric lamp of transmitter L^3 of signaling device N^B is constantly connected with battery U^B , so that this lamp is constantly lighted. 10 Each of the remaining devices N is controlled by the associated relays in the same manner as just described for the control of device N^B by relays T^B and E^B .

As shown in the drawings, sections A—B, 20 B—C, and C—D are all unoccupied, but the section to the right of point D is occupied by train W^1 which is here represented diagrammatically by an axle and a pair of wheels. Track relay T^D is therefore deenergized. Since track relay T^D is deenergized, the circuit for line relay E^D is open at front contact 6 of track relay T^D , and line relay E^D is also deenergized. Furthermore, the circuit for the lamp of transmitter L^1 of signaling device N^D , and the circuit for the lamp of transmitter L^2 of signaling device N^D , are both open at front contact 4 of track relay T^D , and these lamps are therefore extinguished. The lamp of the transmitter L^3 30 of each of the signaling devices N is lighted, since each of these lamps is constantly connected with the associated battery U .

Since section C—D is unoccupied, track relay T^C is energized. Line relay E^C , however, is deenergized, the circuit for this relay being open at front contact 5 of track relay T^C . As a result, the circuit for the lamp of transmitter L^1 of signaling device N^C is open at front contact 8 of line relay E^C , but the circuit for the lamp of transmitter L^2 of signaling device N^C is closed at back contact 8 of line relay E^C , and at front contact 4 of track relay T^C . It will be apparent, therefore, that the lamp of transmitter L^1 of signaling device N^C is extinguished, but the lamps of transmitters L^2 and L^3 of this signaling device are both lighted.

Track relay T^B is energized and line relay E^B is energized in the reverse direction. 55 The circuit for the lamp of transmitter L^1 of signal device N^B is therefore closed at front contact 4 of track relay T^B and at front contact 8 of line relay E^B , so that this lamp is lighted. The lamp of transmitter L^3 of signaling device N^B is also lighted. The circuit for the lamp of transmitter L^2 of signaling device N^B is open at back contact 8 of line relay E^B and the branch for this circuit is also open at normal contact 9 of line relay E^B so that this lamp is extinguished.

Track relay T^A is energized, and line relay E^A is energized in the normal direction. The lamps of the transmitters L^1 , L^2 and L^3 of signaling device N^A are therefore all lighted.

Located in the section to the left of point A is a train W^2 which is here represented diagrammatically by an axle and a pair of wheels. Mounted on this train at some convenient location, or locations, as the case may be, are three relay devices P^1 , P^2 and P^3 . 75 These relay devices are adapted to be selectively operated by the beams of radiant energy transmitted by the transmitters L^1 , L^2 and L^3 , respectively, of the trackway signaling devices N described hereinbefore as the train passes these signaling devices, and are so arranged on the train that each of the relay devices P^1 , P^2 and P^3 will be in the path of the beam transmitted by the corresponding transmitter L of each signaling device N when the train passes the signaling device. For example, if the transmitters L of the signaling devices N are arranged in triangular relation as shown in Fig. 1, the train-carried relay devices P may be similarly arranged on the train so that as the train passes a signaling device N , the beam from each transmitter will strike the corresponding relay device. Or, if the transmitters L of each signaling device N are arranged in a row as shown in Fig. 2, the train-carried relay devices P may be likewise arranged in a row so that each relay device is in the path of the beam from the proper transmitter as the train passes a signaling device. The relay devices P^1 , P^2 and P^3 may have any suitable form, but as here shown, each relay device P comprises a photo-glow tube having two spaced electrodes 24 and 25 enclosed in a sealed envelope filled with a suitable medium such as neon gas, the electrode 25 being constructed of, or coated with, a substance which emits electrons when radiant energy of the proper wave length or wave lengths, such for example as light rays, impinges thereon. If an electromotive force having a magnitude sufficiently great is applied across the electrodes 24 and 25 of a tube of the type described, and the tube is placed in the path of a beam of radiant energy of the proper wave length and of sufficient intensity, the medium between the electrodes becomes conducting, and a current flows from electrode 24 to electrode 25. Furthermore, if the electromotive force applied across the electrodes 24 and 25 of a tube of the type described is unidirectional, and if the tube is once rendered conducting, the tube will remain conducting until the magnitude of the applied electromotive force 100 is decreased to a value which is below the value of the constant potential drop across the medium between the electrodes when the tube is conducting.

A condenser designated by the reference 130

character G with a suitable distinguishing exponent, is connected across the electrodes 24 and 25 of each photo-glow tube P in series with a relay, designated by the reference character F with a distinguishing exponent. One terminal of each condenser G is connected with one terminal of a suitable source of current, here shown as a battery J, and the other terminals of these condensers are connected with the other terminal of the source through individual resistances each designated by the reference character H with a distinguishing exponent. A resistance designated by the reference character R with a distinguishing exponent is also connected across the electrodes 24 and 25 of each tube P over a front contact 26 of the associated relay F.

Referring now particularly to photo-glow tube P¹, with the parts arranged in the manner just described, when this tube is non-conducting, as when no beam of radiant energy is striking the tube, condenser G¹ charges through resistance H¹ until the potential between its plates is equal to the electromotive force of battery J, and an electromotive force equal to the electromotive force of battery J is then applied across electrodes 24 and 25 of tube P¹. The magnitude of this electromotive force is adjusted to have a value which is below the breakdown value for the tube, when no radiant energy is striking the tube, and tube P¹ therefore normally remains non-conducting, so that no current normally flows in the winding of relay F¹. Relay F¹ is therefore normally deenergized. When tube P¹ becomes conducting, however, as when a beam of radiant energy of the proper wave length and intensity, such for example as the beam transmitted by one of the transmitters L¹, strikes tube P¹, condenser G¹ gradually discharges through the winding of relay F¹, and at the same time current from battery J starts to flow through this winding, and through resistance H¹. Relay F¹ therefore becomes energized and closes its front contacts. When front contact 26 of relay F¹ becomes closed, resistance R¹ is then connected across the electrodes 24 and 25 of tube P¹. Due to the characteristic of tubes of this type pointed out hereinbefore, when tube P¹ has once been rendered conducting, the tube will remain conducting, and relay F¹ will therefore remain energized, until the magnitude of the electromotive force impressed across its electrodes decreases below the value for the constant potential drop across the medium between these electrodes when the tube is conducting. The magnitude of the electromotive force impressed across the electrodes 24 and 25 of tube P¹ at any instant after the tube has once been rendered conducting depends upon the electromotive force of battery J, upon the value of the resistance of the winding of

relay F¹, resistance H¹, and resistance R¹, and upon the capacity of condenser G¹. It follows that by properly proportioning these parts, tube P¹ may be made to become non-conducting at the expiration of any desired time interval after the tube has passed out of the beam from the associated transmitter. The parts will usually be so adjusted that this interval will be two or three seconds, but the length of this interval may be varied as conditions require. In order to obtain the proper time intervals with relays of the usual type it may be desired under some conditions to insert additional resistance in series with the relay F¹. When tube P¹ again becomes non-conducting, relay F¹ becomes deenergized and opens its front contacts. Condenser G¹ then again becomes charged to a potential which is equal to the electromotive force of battery J, and the parts are restored to their normal conditions.

The operation of the tubes P² and P³ is similar to that described for tube P¹ and will be readily understood from the foregoing description of the operation of tube P¹.

The function of the resistances R is to bypass current from the associated tube P when this tube P becomes conducting, thereby decreasing the time interval during which the tube will remain conducting.

These resistances also insure that the potential drop across the electrodes of the associated tube will be reduced to the value at which the tube becomes non-conducting while a considerable current from the associated discharging condenser G still flows through the associated relay F, and so prevents the tube discharge being maintained by current from battery J. The release values of the relay F will preferably be such that when these relays have once been energized, they will remain energized until after the associated tube becomes non-conducting, so that the resistances R will remain connected across the associated tube until after the tube becomes non-conducting.

The relays F¹, F² and F³ controlled by the tubes P¹, P² and P³ may be employed to control train-carried governing means of any suitable type. As here shown, these relays control four separate electric lamps S¹, S², S³ and S⁴. When the relay F³ is energized and relays F¹ and F² are deenergized, a circuit is completed for lamp S¹ including a suitable source of current such as a battery M, back contact 27 of relay F¹, back contact 28 of relay F², and front contact 27 of relay F³. When this circuit is closed, lamp S¹ becomes energized to indicate stop. When relays F³ and F² are energized, and relay F¹ is deenergized, a circuit is completed for lamp S³ including battery M, back contact 27 of relay F¹, front contact 28 of relay F², and front contact 27 of relay F³. When this circuit is closed lamp S³ becomes lighted to indicate

caution. When relays F^3 and F^1 are energized, and relay F^2 is deenergized, lamp S^2 becomes energized to indicate approach restricting by virtue of a circuit including battery M , front contact 27 of relay F^1 , back contact 27 of relay F^2 , and front contact 27 of relay F^3 . When relays F^1 , F^2 and F^3 are all energized, lamp S^1 is supplied with current from battery M over front contact 27 of relay F^1 , front contact 27 of relay F^2 , and front contact 27 of relay F^3 . Under these latter conditions, lamp S^1 becomes lighted to indicate proceed.

In explaining the operation of the apparatus as a whole, I will assume that with the trackway apparatus in the condition previously described, and with the train-carried apparatus in its normal condition, the train W^2 traverses the stretch of track indicated in the drawing. Under these conditions, when the train passes signaling device N^A , since the electric lamps of transmitters L^1 , L^2 and L^3 of this signaling device are all lighted, the relay devices P^1 , P^2 and P^3 all become conducting so that the relays F^1 , F^2 and F^3 all become energized. Lamp S^1 therefore becomes lighted to give a proceed indication on the train. This indication continues until the time interval for which the tubes P^1 , P^2 and P^3 are adjusted to remain conducting has expired, at which time the tubes again become non-conducting so that the relays F^1 , F^2 and F^3 become deenergized and deenergize lamp S^1 . The train-carried apparatus is then restored to its normal condition.

When the train passes signaling device N^B , tubes P^1 and P^3 become conducting, but tube P^2 remains non-conducting since only the lamps of transmitters L^1 and L^3 of this signaling device are lighted. Relays F^1 and F^3 therefore become energized, but relay F^2 remains deenergized, so that electric lamp S^2 becomes lighted and gives an approach restricting indication on the train.

When the train passes signaling device N^C , only tubes P^2 and P^3 become conducting so that only relays F^2 and F^3 become energized. Lamp S^3 then becomes lighted during the interval that there relays are energized, thereby giving a caution indication on the train.

At signaling device N^D only the electric lamp of transmitter L^3 is lighted so that only the tube P^3 becomes conducting when the train passes this signaling device. Electric lamp S^4 therefore becomes energized and gives a stop indication on the train.

Under some conditions it is desirable to place the photo-glow tubes close together on the train in order that the apparatus may be constructed in as small a compass as possible. When this is done it may happen that when the train passes a signaling device the beam transmitted by each transmitter will strike more than its corresponding photo-glow

tube. In order to prevent improper operation of the train-carried apparatus under these conditions, each of the transmitters may be provided with a suitable filter which will pass only light rays within a predetermined band of frequencies, and the corresponding photo-glow tube may be provided with a similar filter. As a result, only the proper tube will receive light rays of sufficient intensity to operate the tube even if all photo-glow tubes are illuminated by the light rays of each lamp.

It should be pointed out that when the radiant energy transmitted by the trackway signaling devices is visible light rays, as illustrated in the drawing, the trackway signaling devices may be constructed to serve as visible wayside signals in addition to operating the train-carried apparatus.

Some advantages of railway traffic controlling apparatus embodying my invention are that the apparatus is inexpensive, is simple to construct, and is reliable in operation.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a plurality of train-carried relay devices each adapted to be operated by a beam of radiant energy, a trackway signaling device comprising a plurality of transmitters each arranged when energized to transmit a beam of radiant energy toward a corresponding one of said train-carried relay devices as the train passes said trackway signaling device for operating such relay device, means for selectively energizing said transmitters, and train-carried governing means controlled by said train-carried relay devices.

2. Railway traffic controlling apparatus comprising a plurality of train-carried relay devices each adapted to be operated by a beam of radiant energy, a trackway signaling device comprising a plurality of transmitters each arranged when energized to transmit a beam of radiant energy toward a corresponding one of said train-carried relay devices as the train passes said trackway signaling device for operating such relay device, means controlled in accordance with traffic conditions for selectively energizing said transmitters, and train-carried governing means controlled by said train-carried relay devices.

3. Railway traffic controlling apparatus comprising a plurality of train-carried photo-glow tubes, a trackway signaling device com-

prising a plurality of transmitters each arranged when energized to transmit a beam of radiant energy toward a corresponding one of said photo-glow tubes as the train passes said trackway signaling device for operating such photo-glow tube, means for selectively energizing said transmitters, and train-carried governing means controlled by said photo-glow tubes.

4. Railway traffic controlling apparatus comprising a plurality of train-carried photo-glow tubes, a trackway signaling device comprising a plurality of transmitters each arranged when energized to transmit a beam of radiant energy toward a corresponding one of said photo-glow tubes as the train passes said trackway signaling device for operating such photo-glow tube, means controlled in accordance with traffic conditions for selectively energizing said transmitters, and train-carried governing means controlled by said photo-glow tubes.

5. Railway traffic controlling apparatus comprising a plurality of train-carried photo-glow tubes, a trackway signalling device comprising a plurality of transmitters each arranged when energized to transmit a beam of radiant energy toward a corresponding one of said photo-glow tubes as the train passes said trackway signaling device for operating such photo-glow tube, means controlled in accordance with traffic conditions for selectively energizing said transmitters, a plurality of relays on the train one controlled by each of said photo-glow tubes, and train-carried governing means controlled by said relays.

6. In combination, a train-carried tube comprising two spaced electrodes enclosed in a medium which forms a conducting path between the electrodes when an electromotive force of sufficient magnitude is applied across said electrodes and the tube is placed in the path of a beam of radiant energy of the proper wave length and of sufficient intensity, a relay, a resistance, a source of electromotive force, means including said relay and said resistance for connecting said source across the electrodes of said tube, a condenser connected across the electrodes of said tube in series with the winding of said relay, means located in the trackway for at times transmitting a beam of radiant energy toward said tube to render said tube conducting, and governing means on the train controlled by said relay.

7. In combination, a train-carried tube comprising two spaced electrodes enclosed in a medium which forms a conducting path between the electrodes when an electromotive force of sufficient magnitude is applied across said electrodes and the tube is placed in the path of a beam of radiant energy of the proper wave length and of sufficient intensity, a relay, a resistance, a source of elec-

ing means on the train controlled by said relays.

9. In combination, a train-carried tube comprising two spaced electrodes enclosed in a medium which forms a conducting path between the electrodes when an electromotive force of sufficient magnitude is applied across said electrodes and the tube is placed in the path of a beam of radiant energy of the proper wave length and of sufficient intensity, a relay, a first resistance, a source of electromotive force, means including said relay and said first resistance for connecting said source across the electrodes of said tube, a second resistance, means including a front contact of said relay for connecting said second resistance across the electrodes of said tube, a condenser connected across the electrodes of said tube in series with the winding of said relay, means located in the trackway for at times transmitting a beam of radiant energy toward said tube to render said tube conducting, and governing means controlled by said relay; the values of said first and second resistances, the resistance of the winding of said relay, and the capacity of said condenser being such that when said tube has once been rendered conducting the electromotive force impressed across the electrodes of said tube will be decreased in a predetermined length of time to a value which is below the constant potential drop between said electrodes when said tube is conducting.

10. In combination, a train-carried tube comprising two spaced electrodes enclosed in a medium which forms a conducting path between the electrodes when an electromotive force of sufficient magnitude is applied across said electrodes and the tube is placed in the path of a beam of radiant energy of the proper wave length and of sufficient intensity, a source of electromotive force, two resistances connected in series with said electrodes and said source, a condenser connected across said electrodes and one of said resistances, a third resistance, means responsive to the current in said one resistance for at times connecting said third resistance across the electrodes of said tube, means located in the trackway for at times transmitting a beam of radiant energy toward said tube to render the tube conducting, and governing means on the train responsive to current in said one resistance.

11. In combination, a train-carried tube comprising two spaced electrodes enclosed in a medium which forms a conducting path between the electrodes when an electromotive force of sufficient magnitude is applied across said electrodes and the tube is placed in the path of a beam of radiant energy of the proper wave length and of sufficient intensity, a source of electromotive force, two resistances connected in series with said electrodes and said source, means located in the track-

way for at times transmitting a beam of radiant energy to said tube to render the tube conducting, a condenser connected across said electrodes and one of said resistances, a third resistance, means responsive to the current in said one resistance for at times connecting said third resistance across the electrodes of said tube; said three resistances and said condenser cooperating to render the tube non-conducting at the expiration of a definite time interval after the tube becomes conducting.

In testimony whereof I affix my signature.
PAUL N. BOSSART.
